PULSE SIGNALING SYSTEM

Emile Labin, New York, and Donald D. Grieg,
Forest Hills, N. Y., assignors to Federal Tele-
phone and Radio Corporation, New York, N. Y.,
a corporation of Delaware

Application April 17, 1945, Serial No. 588,844

17 Claims. (Cl. 250—20)

1

This invention relates to pulse signal systems of the pulse time or phase displacement character.

In transmitting systems employing pulse time or phase displacement principles, a certain amount of interference occurring during the time intervals between the pulses can be removed by blocking the interval occurring between the limits of modulation of the pulses. This form of interference elimination is particularly helpful where the maximum displacements of pulses are small compared to the time intervals between maximum limits of displacement of the pulses. Another useful method of increasing signal-to-noise ratio is to increase the maximum limits of time modulation in the transmitter. This effect, however, reduces the permissible blocking intervals in the receiver so that little net gain in signal-to-noise ratio is obtained.

It is an object of this invention to provide a system utilizing both of the above mentioned methods of improving signal-to-noise ratio in pulse systems operating on the time displacement principle of modulation.

Another object is to provide a method and means for changing the time displacement of pulse time modulated signals either to reduce or to increase the time displacements of the pulses, as may be desired.

Another object of the invention is to provide a method and means for feeding back signal energy, either as a positive or negative feedback, in pulse time demodulator systems for changing substantially proportionately the time displacements of the time modulated pulses.

Another object is to provide a pulse time modulation receiver with means for changing, either to reduce or increase, the time displacement of the time modulated pulses and to block the intervals provided between the pulses, either before or after the time displacement changing operation.

A feature of the invention is to provide a feedback arrangement for either increasing or decreasing proportionately the time displacements of T. M. (time modulated) pulses. According to one method of the invention, the signal energy is obtained by translating the time displacements into audio frequency energy and then applying the audio energy to a modulator circuit located in the input connection to the T. M. (time modulation) demodulator. Where it is desirable to reduce the degree of time displacement of the pulses, this may be accomplished by inverting the phase of the audio frequency energy so as to modulate the time modulated pulses in an oppo-

2

site direction with respect to the initial modulation. The amount of feedback or change in time displacement may be determined by controlling the amplitude of the feedback energy. To increase the time displacements the feedback energy is applied in phase with the modulation so as to add further to the time displacements in the same direction as initially applied.

According to a further feature of the invention, the interference occurring between the pulses, particularly between the limits of modulation thereof, may be blanked out by a suitable blocking wave produced in response to the average timing of the time modulated pulses. This blanking operation, however, may be performed by waves produced directly in response to each individual pulse as it is received, each resulting wave or undulation being used for blanking the interval following the pulse. The blanking operation may also be located either prior to the time displacement changing circuit or at a point following it.

For a better understanding of the objects and features of the invention, reference may be had to the following detailed disclosure and the accompanying drawings in which:

Fig. 1 is a schematic diagram of a receiver circuit according to the invention;

Fig. 2 is a graphical illustration useful in explaining the operation of the invention; and

Fig. 3 is a schematic diagram of a modified form of the invention.

Referring to Fig. 1, a radio carrier receiver and detector 1 is shown for receiving by means of antenna 2, pulse modulated carrier energy from a transmitter 3 where the pulses are time modulated with respect to a regular timing in response to intelligence signals. According to the present invention the time displacements at the transmitter 3 are large so as to provide an improved signal-to-noise ratio for the signals for transmission.

In Fig. 2, graph A shows a sinusoidal signal wave 4 representative of the modulating energy that may be employed at the transmitter 3. The graph B represents a blocking wave 5 and a train of time modulated pulses 6 to 14 received from transmitter 3 and detected at 1, the pulses being modulated according to the wave energy 4. The detected pulses 6 to 14 are shown to be time displaced between the limits of modulation 15, 16, the pulses 6 and 14 representing the maximum negative modulating signal potential and the pulse 10 representing the time positions after modulation in response to the maximum positive

signal potential. The other pulses represent time displacements varying between these two limits, the pulses 8 and 12, for example, representing zero modulation. The wave 5 represents a blocking potential that may be used for blanking out interference and other energy occurring during the time intervals between limits 15 and 16 of adjacent pulses.

The pulses 6 to 14 are applied over connection 17, Fig. 1, to a time displacement changing circuit 18 which may be in the form of any one of a plurality of pulse time modulating circuits depending, of course, upon the particular type of pulse time modulation employed. The form shown for purposes of illustration is of the inductance delay type whereby the input pulses are delayed more or less depending upon the amplitude of the potential applied thereto over connection 19. This type of modulator circuit is disclosed in the copending application of Emile Labin, Serial No. 546,378, filed July 24, 1944, now Patent No. 2,445,783, which issued July 27, 1948. The circuit includes an inductance coil 20 having an iron core 21. The input connection 17 is applied thereto through a blocking condenser 22 and the ends of the coil 20 are connected through condensers 23 and 24 to ground.

The output of the modulator circuit 18 is preferably applied to an amplifier 25 and then to a T. M. demodulator 26 whereby the time displacements of the pulses are translated into amplitude displacements and applied to a low pass filter 27 to remove the pulse component. This results in an audio signal wave which may be applied directly to earphones 28 or other utilization circuits. The audio signal wave is also applied over connection 29 to a phase inverter 30, amplitude control device 31, the gain of which may be adjusted, and thence over connection 19 to the modulator 18.

In Fig. 2, graph C represents the audio signal wave 22 after the phase and amplitude thereof has been controlled as desired at 30 and 31. It will be understood, of course, that the time relationship of the different graphs in Fig. 2 may be varied in actual practice from that shown, but for purposes of illustration the relations shown may be regarded as indicating the operating principles of the invention. When the wave 32 is applied to the modulator 18, the pulses 6 to 14 applied thereto over connection 17 are further displaced according to the potential of the wave 32, the amplitude of which is controlled at 31. This further modulation changes the time positions of the input pulses substantially as indicated at 6' to 14', graph D. Referring particularly to pulse 6, the time position of which corresponds to the maximum negative potential of the initiating modulating wave 4, the new position indicated at 6' is displaced an amount t_1 equal to substantially one half the amount of the maximum displacement indicated by limits 15 and 16. The pulse 10 which corresponds to the maximum positive potential of the signal is theoretically undisturbed by the modulating operation of circuit 18. As a matter of fact, some modulation will occur due to the displacement relation of pulse 10 with respect to the maximum positive potential point on curve 32, but this is only a slight amount compared to the modulation of pulse 6. The pulses 7, 8 and 9 between these two limits are shifted in time displacement by amounts t_2 , t_3 and t_4 respectively corresponding to the amplitude and phase of the feedback energy 32.

For simplicity of illustration, any inherent de-

lay produced by the circuit 18 for modulating energy corresponding to the negative maximum of signal wave 32 has been disregarded. Other types of modulating circuits having zero or some other modulating effect for the maximum negative potential value may be used in place of the particular modulator 18.

Graph E represents the signal pulses as they occur in the output of the circuit 18, the new limits of modulation being indicated at 15' and 16'. It will be clear that the intervals T_1 occurring between the limits of modulation of adjacent input pulses, graph B, are considerably smaller than the intervals T_2 occurring between the limits of modulation of the output pulses of circuit 18. By applying the signal pulses over connection 33 to a tuned circuit of a known wave producer 34, a suitable blocking wave having a frequency corresponding to the average repetition rate of the signal pulses may be obtained. By shaping and phasing the wave at 35, a substantially rectangular blocking wave 36 is produced as a control potential for amplifier 25, whereby interference or other energy occurring during the intervals between the pulses is blanked out. It will be clear according to our invention that the reduction of the time displacement of the pulses at the receiver enables the blanking out of a much greater time interval than was possible prior to the displacement reduction as is clear from a comparison of blocking waves 5 and 36.

In Fig. 3, a circuit has been shown similar to Fig. 1 except that the feedback energy is fed back in phase with respect to the phase of the initial modulating signal energy. The phase inverter 30 therefore has been omitted in this embodiment. The other elements are the same as indicated by like reference characters except that the amplifier 25 is located in the input to modulator 18 as indicated at 25a. It will be clear that the feedback of audio wave energy from filter 27 to the modulator 18 being in phase with the initial modulation of the time modulated pulses applied to the modulator 18 will act in the nature of a positive feedback energy and thereby increase further the time displacements of the time modulated pulses. In this connection, it might be added that increased time displacement is desirable for certain forms of demodulator circuits. In such a circuit, the blocking operation is preferably performed before the time displacement changing operation. Thus, the amplifier 25a is controlled by the blocking wave from generator 34 to blank out any interference occurring in the intervals between input pulses.

Those skilled in the art will recognize that many changes and various modifications of the invention may be made without departing from the principles thereof. For example, either push-pull time modulated pulses, a different form of modulator and possibly also a different form of demodulator may be employed, and it may be desirable even to use other circuits in conjunction with the modulating feedback operation. It is to be understood, therefore, that the embodiments herein shown and described are submitted by way of illustration of the invention only and not as a limitation of the scope of the invention as set forth in the objects and the appended claims.

We claim:

1. A method of changing the time displacement of time modulated pulses comprising de-modulating the time modulated pulses to obtain the signal energy thereof, and time modulating

the time modulated pulses with the energy thus obtained.

2. A method of changing the time displacement of time modulated pulses comprising demodulating the time modulated pulses to obtain the signal energy thereof, time modulating the time modulated pulses with the energy thus obtained, and controlling the amplitude of the signal energy to determine the amount of change desired by the modulating operation.

3. A method of reducing the time displacement of time modulated pulses comprising demodulating the time modulated pulses to obtain the signal energy thereof, and time modulating the time modulated pulses in phase opposition with respect to the phase of the initial modulation of the pulses.

4. A method of increasing the time displacements of time modulated pulses comprising demodulating the time modulated pulses to obtain the signal energy with which the pulses are modulated, and time modulating the time modulated pulses with the signal energy thus obtained in phase with the initial modulation of the pulses.

5. A method of improving the signal-to-noise ratio of time modulated pulses comprising reducing the time displacement of the pulses to increase the time interval between the maximum limits of time modulation of the pulses, and blocking the energy occurring during said time intervals.

6. A method of improving signal-to-noise ratio of time modulated pulses comprising reducing the time displacements of the pulses, and blocking the energy occurring during the time intervals resulting between the new time modulation limits of the pulses.

7. A method of improving signal-to-noise ratio of time modulated pulses comprising increasing the time displacements of the pulses, and blocking the intervals between the time modulation limits of the pulses prior to the displacement increasing operation.

8. A method of improving signal-to-noise ratio of time modulated pulses comprising reducing the time displacements of the pulses, translating the time modulation of said pulses into amplitude modulated energy, applying said energy in phase opposition to the modulation of said pulses as a further modulating energy to reduce the time displacements of said pulses, and blocking the energy occurring during the time intervals resulting between the new time modulation limits of the pulses.

9. Means for changing the time displacement of time modulated pulses comprising means for translating the time modulated pulses into amplitude modulated energy, and means to modulate in time the time modulated pulses according to the amplitude modulated energy thus obtained.

10. A means according to claim 9 wherein the means for translating the time modulated pulses include means for controlling the amplitude of the amplitude modulated energy.

11. A means according to claim 9 wherein the means for translating the time modulated pulses include means for controlling the phase of said energy to determine the direction of the change in time displacement.

12. A means according to claim 9 wherein the

means for translating the time modulated pulses include means for controlling the phase and amplitude of said energy to determine the degree and direction of the change in the time displacement.

13. Means for changing the time displacement of time modulated pulses comprising a time modulator, means to apply time modulated pulses to said modulator, a demodulator for translating the pulse output of said modulator into amplitude modulated energy, and means to apply the output energy of said demodulator to said modulator to vary the time displacement of the pulses.

14. Means for changing the time displacement of time modulated pulses comprising a time modulator, means to apply time modulated pulses to said modulator, a demodulator for translating the pulse output of said modulator into amplitude modulated energy, means to control the phase of said energy, and means to apply the output energy to said modulator to vary the time displacement of the pulses applied thereto according to the amplitude and phase relation of said energy.

15. Means for improving the signal-to-noise ratio of time modulated pulses comprising means for translating input time modulated pulses into amplitude modulated energy, means responsive to said energy to reduce the time displacement of said pulses, a blocking circuit, and means to derive a blocking wave from the average timing of said pulses for application to said blocking circuit to blank out energy occurring during the major part of the intervals between the pulses following the displacement reduction thereof.

16. In a receiver for time modulated pulses, a time displacement changing circuit, means to apply the input time modulated pulses to said circuit, a demodulator for translating the time modulated displacements of said pulses into amplitude varying energy, means for inverting the phase of said output energy, means to control amplification of said energy, means to apply the output energy thus controlled as to phase and amplitude to said displacement changing circuit to modify the time displacements of said input pulses, means controlled by said input pulses to produce a blocking wave and means employing said blocking wave to block energy occurring during the time intervals between time modulated pulses enlarged by said displacement changing circuit.

17. In a receiver for time modulated pulses, a time displacement changing circuit, means to apply the input time modulated pulses to said circuit, an amplifier to receive the output of said circuit, a demodulator for translating the time modulated displacements of said pulses into amplitude varying energy, means for inverting the phase of said output energy, means to apply the output energy thus controlled as to phase to said displacement changing circuit to modify the time displacements of said input pulses, means controlled by said input pulses to produce a blocking wave, and means to apply said blocking wave to said amplifier to block the intervals between time modulated pulses.
